CLAIM

The ornamental design for a front facia for an automobile, as shown and described.

DESCRIPTION

FIG. 1 is a perspective view of a front facia for an automobile;

FIG. 2 is a front view thereof;

FIG. 3 is a side view thereof, the opposite side being a mirror image;

FIG. 4 is a top view thereof;

FIG. 5 is a bottom view thereof; and,

FIG. 6 is a front perspective view thereof attached to an automobile.

The broken line showing of an automobile is for illustrative purposes only and forms no part of the claimed design. The broken line showing of any internal surfaces of the front facia forms the bounds of the claimed design but not part of the claimed design.
